BOTTLE FOR DISPENSING LIQUID MATERIAL

Yoshio Abe, Tokyo, Japan, assignor to Kikkoman Shoyu Co., Ltd., Noda City, Japan, a corporation of Japan

Filed Apr. 18, 1966, Ser. No. 1,921

Term of patent 14 years

(Cl. D9—97)

FIG. 1

FIG. 2

FIG. 6

FIG. 4

FIG. 5

FIG. 3

FIG. 1 is a front elevational view of a bottle for dispensing liquid material embodying my new design;

FIG. 2 is a side elevational view;

FIG. 3 is a bottom plan view;

FIG. 4 is a perspective view;

FIG. 5 is a side elevational view with the cap removed; and

FIG. 6 is a fragmentary view of the top portion with the cap removed.

I claim:

The ornamental design for a bottle for dispensing liquid material, as shown.
